UNITED STATES PATENT OFFICE.

SAMUEL W. WARRINGTON, OF EL PASO, TEXAS.

SNAP-FASTENER.

1,366,105.

Specification of Letters Patent. Patented Jan. 18, 1921.

Application filed June 16, 1920. Serial No. 389,335.

To all whom it may concern:

Be it known that I, SAMUEL W. WARRINGTON, a citizen of the United States, residing at El Paso, in the county of El Paso and 5 State of Texas, have invented new and useful Improvements in Snap-Fasteners, of which the following is a specification.

This invention relates to improvements in fastening devices and resides in the provision of a simply constructed, inexpensive, and efficient fastening device which may be used for the usual purpose of snap buttons, hooks, and eyes, and similar fasteners, and which eliminates the necessity of sewing the 15 fasteners in place upon garments.

An object of the invention is to provide a fastening device of the character described which consists in male and female members, each of which is constructed of a single 20 piece of material and in such manner that it may be easily and quickly hooked in place upon a garment or the like and will remain in such position without necessitating being sewed in place.

25 A further object is to provide a fastener of the character described which will be of particular use for ladies' dresses and similar garments in that they may be quickly substituted for hooks and eyes or the ordinary snap fasteners which have been torn off or pulled out of such garments and which will serve to reliably hold the garment together.

Figure 1 is a top plan view of the male fastener of the invention.

35 Fig. 2 is a top plan view of the female fastener of the invention.

Fig. 3 is a side elevation of the member of Fig. 1.

Fig. 4 is a side elevation of the member 40 of Fig. 2.

Fig. 5 is a top plan view showing said members snapped together.

Fig. 6 is a top plan view of the manner of attaching one of the members to a dress or 45 other garment.

Referring to the present embodiment of the invention there is provided a male fastening member 7 and a female fastening member 8. The male member 7 is formed 50 of a single piece of preferably resilient wire bent substantially centrally of its ends to provide a straight portion 9 and then doubled back upon the straight portion 9 from each end thereof, as at 10 and 11, said 55 portions 9, 10, and 11 forming the body of said member 7. The doubled back portions

are disposed in the same plane as the portion 9 and each terminates substantially centrally of the ends of the portion 9. The wire is extended from the portion 11 outwardly and is then bent upwardly in the form of a loop 12. From the loop 12 the wire is extended and bent into a substantially U-shaped portion, as at 13, with one side of the U-shaped portion comprising a 60 prong 14 provided with a pointed end 15. This prong 14 is adapted to rest at its pointed end 15 upon the bent back portion 10, said portion 10 serving as a guard. The bent back portion 10 is extended outwardly 65 and then bent forwardly to form a loop 17 corresponding to and engaging the loop 12. These two loops together form the male snap element generally designated 16. From the loop 17 the wire is bent into U- 70 shaped form and lies in the same plane with the portions 9 and 11. One side of said U-shaped portion serves as a prong 18 and is provided with a pointed end 19, which latter rests upon the bent back portion 11 after 75 the manner of the prong 14.

All of the parts of the member thus formed except the male member 16 lie substantially flat and in the same plane. To secure the member 7 to a garment or the like, 80 it is only necessary to insert the pointed prongs 14 and 18 through the material after the manner of inserting a safety pin and so that the pointed ends 15 will rest upon the portions 10 and 11 of the body. 90

The female member 8 comprises a single piece of small resilient wire bent approximately centrally of its ends to provide a straight portion 20 and then bent back upon the portion 20 to provide the portions 21 and 22 corresponding to the portions 10 and 11, and which, with the portion 20, provide the body of the member. The portion 21 terminates at a point substantially centrally of the end of the point 20 then extends outwardly 100 into substantially U-form, as at 23. The portion 22 is likewise bent into U-form, as at 24, said U-portions crossing one another and being bent in such a manner as to provide an approximately circular opening 25 105 adapted to receive the male member 16. By reason of the wire being resilient, the member 16 will force the sides of the U-portions 20 and 23 apart in being entered in the opening 25 and said parts will snap back into 110 place and retain the member 16 after the manner of the ordinary snap fastener. The

other sides of the U-portions 23 and 24 lie at right angles to the body to provide prongs 26 having pointed ends 27. The ends 27 are adapted to engage under the portions 21 and 5 22 and to lie between these portions and the straight portion 20. To fasten this member 8 it is only necessary to insert the prongs 26 into the material of the garment after 10 the manner of inserting a safety pin and to dispose the pointed ends 27 under the portions 21 and 22 and between said portions and the portion 20.

It will thus be seen that I have provided male and female snap fastening elements, 15 each made of a single piece of wire and that I have provided for a quick and reliable attachment of said fasteners by reason of the prongs formed by a peculiar bending of the free ends of the wires of which said fastening 20 elements are formed.

With fasteners of this invention, the attachment thereof to garments may be effected much more easily and quickly than the ordinary snap fastener or hooks and eyes.

25 While I have illustrated and particularly described the invention, it is to be understood that I may vary the manner of bending the wire, provided, however, that such bending falls within the spirit and scope of 30 the invention.

The invention, broadly speaking, contemplates the provision of male and female snap fasteners formed of single strands of wire bent so as to provide male and female 35 fastening elements and means in the nature of a pin for securing the fasteners in place, said elements being so related that sufficient body is provided for the fasteners to securely fasten the device to garments.

I claim:—

1. A fastening element of the character described embodying in its construction a single piece of wire bent intermediate of its ends to provide oppositely extending guard portions, then bent to one side of said guard 45 portions to provide one of the elements of a snap fastener at a point spaced from the guard portions, and then having its free end bent to extend on opposite sides of the said element and pointed, with the pointed ends 50 arranged to rest upon the guard portions.

2. A fastening device embodying in its construction a single piece of wire bent intermediate of its ends to provide oppositely extending guard portions, then bent to provide one element of a snap fastener on one side and independent of said guard portions, and further bent to provide prongs at the free ends of the wire, which prongs extend on opposite sides of and in spaced relation 60 to said element with their ends arranged to engage said guard portions.

3. A fastening device comprising male and female members each of which embody a single piece of resilient wire bent 65 intermediate of its ends to provide guard portions and then bent at right angles to the guard portions to provide one of the elements of a snap fastener at a point spaced from said guard portions and then bent into 70 substantially U-shaped form with its free ends extending on opposite sides of and adapted to engage said guard portions, said element being disposed substantially at a central point of the entire fastening device, 75 said free ends being pointed.

SAMUEL W. WARRINGTON.
